(57) **CLAIM**

The ornamental design for a wing-shaped handbag, as shown and described.

DESCRIPTION

FIG. 1 is a front perspective view of a wing-shaped handbag, showing the present design.

FIG. 2 is a front view of the wing-shaped handbag, showing the present design.

FIG. 3 is a rear view of the wing-shaped handbag, showing the present design.

FIG. 4 is a right side view of the wing-shaped handbag, showing the present design.

FIG. 5 is a left side view of the wing-shaped handbag, showing the present design.

FIG. 6 is a top view of the wing-shaped handbag, showing the present design; and,

FIG. 7 is a bottom view of the wing-shaped handbag, showing the present design.

The dashed broken lines showing the strap are for illustrative purposes and form no part of the claimed design. The dotted broken lines shown on the wing-shaped handbag depict stitching and are included in the claimed design.

1 Claim, 7 Drawing Sheets
